8 Claims. (Cl. 250—27.5)

1

Mercury vapour discharge vessels are known especially as rectifier vessels, wherein the mercury vapour arc is ignited with the aid of a magnetic field.

Such vessels contain an annular anode, the annular surface of which is found parallel to the mercury level of the cathode, several cathode plates consisting of metal surface of which lie parallel to the annular surfaces of the anodes, and a cathode consisting of liquid mercury. The anode annular surface and the cathode plates are penetrated by a magnetic constant or alternating field, the cathode plates are connected conducting together and with the mercury cathode. These plates are designated hereinafter, metal cathodes, in contradistinction to the mercury cathode.

The magnetic field is produced by a solenoid coil or by a permanent magnet of suitable form.

It cuts the metal cathode surfaces substantially vertically.

In order to keep the ignition voltage of such vessels as low as possible, the latter are furnished with inert gas filling of a pressure of at least 0.03 mm. mercury column.

The manner of operation of these discharge vessels is the following: If a voltage is applied between the anode and the cathode, in such manner that the anode is positive as compared with the cathode, then there originates firstly between the metal cathode and the anode, a glow discharge which ignites at about 300 volts. When the voltage rises to 400-500 volts, the glow current rises to about 10-20 milliamperes, whereby the glow discharge suddenly passes over into the mercury vapour arc. Therefore a cathode spot is ignited upon the surface of the mercury cathode. For this purpose a magnetic field intensity of 500 to 700 Gauss is required in the centre of the anode annular surface. The ignition voltage rises with reduced magnetic field intensity, against which an increase of the same over and beyond these values usually brings about no substantial decrease of the ignition voltage.

Hereinafter that voltage is termed ignition voltage, which is present at the moment of the ignition of the arc between the anode and the mercury cathode.

The glow current which flows previous to the ignition of the arc between the anode and the metal cathode, is termed hereinafter ionization current.

If an alternating voltage is applied between the anode and the cathode, then the process of ignition is repeated in each cycle of the alternating voltage.

In order to obtain with such vessels, faultless manner of operation as rectifiers, in the first place various technical difficulties must be overcome. Especially, the ignition voltage is not stable, but

2

fluctuates permanently within wide limits; also it rises with increasing temperature, therefore, rising mercury vapour pressure, under certain circumstances to 2000 and more volts.

Since the anode and the metal cathode must lie very close together, particularly in the case of high vapour pressures, the danger of back ignition is very great. In particular, these back ignitions occur between the metal cathode and the anode.

The present invention relates to several embodiments of such vessels which prevent the difficulties mentioned, as well as to an arrangement which is suitable for controlling such vessels in simple manner. Finally, arrangements are proposed in order to attain the production of the magnetic field with as low as possible an outlay.

In Figs. 1 to 6, vessels in conformity with this invention are illustrated. One embodiment is shown in Fig. 1. 1 is the glass flask, 2 and 3 are circular cathode plates which are connected conducting by means of the holder 4. The plates 2 and 3 are attached to the supply lead 12. 2, 3, 4 and 12 together form the metal cathode. 5 is the annular anode which is connected with its supply lead 7 through the device 6. 8 is the mercury cathode and 19 the supply lead to the same. The axial magnetic field is produced by the magnet coil 9 which may be fed with direct or alternating current. If the magnet coil is fed with alternating current the phase position of the supply voltage as compared with that of the anode alternating voltage is to be selected in such manner that the coil flux at the ignition point attains approximately its maximum.

The glow discharge, which at times precedes the cathode spot ignition, originates in the space within the anode ring 5 between the two metal cathode plates 2 and 3. The ionization current flows from the anode 5 on to the metal cathode. As shown in the figure, the lower cathode plate 3 is equipped in its centre with a circular opening. This measure has turned out to be advantageous in order to facilitate the ignition of the arc. The opening in the plate 3 makes a connection between the discharge space of the glow discharge and the mercury cathode. Instead of one circular-shaped opening, the plate 3 may be provided with several small openings or may be constructed as wire grid.

For the perfect working of the vessel, the distance between the lowest cathode plate 3 and the surface of the mercury cathode, is of paramount importance. When the tube is cold, therefore, with low mercury vapour pressure, the ignition takes place faultlessly if this distance amounts to up to 40 mm. But in order to attain stable ignition voltage even with high vapour pressure, this distance must amount to less than 10 mm.

In order that the ignition of the arc may be

possible, the metal cathode must be connected conducting with the mercury cathode. As mentioned, at high vapour pressures there is particular danger of back ignitions especially between the metal cathodes and the anode. One very effective measure to make these back ignitions non-prejudicial, consists in connecting the metal cathodes system across a resistance with the mercury cathode. An eventual back ignition current between metal cathode and anode is then damped by this resistance and the back ignition is immediately extinguished after its ignition.

In that the metal cathode and the mercury cathode are connected across a resistance, the ignition voltage of the vessel is somewhat raised since also the ionization current is reduced through this resistance and therefore a higher voltage is required in order to attain this.

If the resistance between the metal cathode and the mercury cathode is made variable, then the possibility is offered, in rectifier operation, to control the direct voltage within certain limits, by altering this resistance.

The ignition voltage rises when the resistance is increased and thereby the direct voltage falls, since the ignition voltage and the direct voltage are indirectly proportional within certain limits.

If use is made of this control possibility the metal cathode must be furnished with a separate supply lead as shown in Fig. 1. The variable resistance is then arranged outside the vessel and connects the supply leads 12 and 19.

A further embodiment according to this invention is shown in Fig. 4. 1 is the glass flask, 9 the magnet coil, 19 the cathode supply lead, 7 is the anode supply lead, 8 the mercury cathode.

Here the anode consists of 4 rings of equal size 5, which are connected together and with the anode supply lead through the holder 6. The metal cathode consists of the three plates 3 perforated in the centre which are found between the anode rings 5 of the lowest plate 17, which likewise is perforated in the centre and of the top solid plate 2. All five metal cathode plates are connected together by means of the holder 4, the entire metal cathode system is attached in the vessel by means of the holder 12.

As will be seen here, 4 discharge spaces are available for the ionization current. This measure has turned out to be most advantageous, to keep the ignition voltage low. The ionization current required for the ignition of the arc is reached at a fairly low voltage as compared with a construction with only one single discharge space.

Also here the distance between the lowest cathode 17 and the mercury level is to amount to less than 10 mm., in order to reach a stable ignition voltage at high temperature.

The metal cathode and the mercury cathode are here connected across a resistance 16 which is arranged inside the tube, in the form of a pin consisting of a material with high electric resistance, for example graphite or silicon carbide in order as hereinbefore stated, to damp any eventual back-ignition currents.

Through this resistance 16 flows likewise the ionization current. Since the latter is of the order of magnitude of about 10 ma, and only flows during a fraction of the cycle of the alternating current, the loss output in this resistance is very slight.

For slightly-loaded tubes, the connection between metal cathode and mercury cathode may be effected also by a metal pin.

In order to keep as low as possible, the electrical output of a magnetic coil required for the production of the magnetic field, or the outlay on material for a permanent magnet, it is recommended to take steps to concentrate the magnetic flux within the anode ring.

According to the present invention this is attained by the arrangement of guiding devices consisting of magnetic material within the tube as shown in Figs. 2, 3, 5, and 6.

Fig. 2 shows a vessel in which the magnetic field is produced by a permanent magnet, seen at the top in meridian section and at the bottom in section vertical to the axis of the vessel. The permanent magnet consists of the magnet steel 13 with the pole-shoes 14 which consists of soft iron. 1 is the glass flask. The anode consists of the two rings 5, but the number selected may be as great as desired. These are connected together and with the anode supply lead 7, through the holder 6. Within the tube the magnetic flux of the permanent magnet is directed by the two guides 10 and 11 consisting of soft iron. The lower guide 11 is found in the cathode mercury 8, below the level or surface, and is held by the cathode supply lead 19. The upper guide 10 serves at the same time as uppermost cathode plate. It is connected conducting with the two annular perforated cathode plates 2 through the holder 4. The entire metal cathode is attached to the holder 12 in the vessel.

Both guides 10 and 11 are supported against the glass wall of the flask through the medium of intermediate pieces 15 consisting of ceramic material.

This measure is necessary, since the guides are pressed through the magnetic pull, against the glass wall.

The metal cathode is connected to the mercury cathode through the medium of the pin 16. The latter may consist of resistant material or of metal.

If alternating current is used for the production of the magnetic field, then the magnetic guides are not to be solid, in order to avoid eddy current losses. According to this invention, they are made of metal strips as shown in Figs. 5 and 6. Figs 5 and 6 show at the top a meridian section through the vessel and at the bottom, a section vertical to the axis of the vessel. 1 is the glass flask, 9 the magnet coil, which is preferably supplied with alternating current, 5 is the anode ring. Also here as in Figs. 2, 3 and 4, several parallel anode rings may be provided.

10 and 11 are the two guides for the magnetic flux, which bring about a concentration of the flux within the anode ring. They consist of strips of magnetic sheet-metal distanced from each other and held together by the pins 18.

60 The lower guide 11 is found in the cathode mercury 8 under the level of the same and is attached to the cathode supply lead 19.

The upper body 10 serves at the same time as top cathode plate. It is fixed to the holder 12 and connected with the lower perforated cathode plate 3 by the holder 4. The pin 16 which again may be constructed as resistance, connects the metal cathode and the mercury cathode.

65 Electrode arrangements as described here consisting of anode rings, metal cathode plates and magnetic field, may likewise be used as ignition device and control device in mercury vapour discharge vessels with one or more main anodes. The main anodes in this case are built into the vessel in the usual arrangement of mercury

vapour vessels. The ignition system consisting of the metal electrodes according to this invention and of the magnetic field, is then arranged directly over the level of the mercury cathode of the vessel and serves for the ignition of the cathode spot as well as eventually, for the control of the instant of the ignition insofar as it is a matter of a vessel with only one main anode. The anode ring of the ignition system then carries only a small current of about 0.1 amp., which is sufficient to ignite the cathode spot, whilst the main current of the vessel is conducted through the main anodes. The control of the instant of time of the ignition is brought about, in that the phase position of the voltage of the ignition anode or the phase position of the supply voltage of the magnet is displaced as compared with that of the voltage of the main anode. Thereby the instant of time of the ignition of the main anode within the positive half-wave of the main anode voltage, is displaced in the same way as this can be attained by means of control grids in known manner.

Having now particularly described and ascertained the nature of my said invention and in what manner the same is to be performed, I declare that what I claim is:

1. A mercury vapour discharge device, comprising in a vessel a mercury cathode, an annular anode in a plane parallel to the mercury surface, cathode plates on both sides of said anode and parallel thereto, the cathode plate nearer to the mercury level being at a distance less than 10 mm. therefrom and a magnet so positioned with respect to said elements that the field of it passes through said cathode plates at right angles with their surface.

2. A mercury vapour discharge device, comprising in a vessel a mercury cathode, an annular anode in a plane parallel to the mercury surface, cathode plates on both sides of said anode and parallel thereto, the cathode plate nearer to the mercury level being at a distance less than 10 mm. therefrom and an electromagnet so positioned with respect to said elements that the field of it passes through said cathode plates at right angles with their surface.

3. A mercury vapour discharge device, comprising in a vessel a mercury cathode, a plurality of annular anodes in planes parallel to the mercury surface, cathode plates alternated with said anodes and parallel thereto, the cathode plate nearer to the mercury level being at a distance less than 10 mm. therefrom and a magnet so positioned with respect to said elements that the field of it passes through said cathode plates at right angles with their surface.

4. A mercury vapour discharge device, comprising in a vessel a mercury cathode, an annular

anode in a plane parallel to the mercury surface, cathode plates on both sides of said anode and parallel thereto, the cathode plate nearer to the mercury level being at a distance less than 10 mm. therefrom, and a magnet so positioned with respect to said elements, that the field of it passes through said cathode plates at right angles with their surface, a set of strips of magnetic metal extended in the direction of the magnetic flux being provided on each side of the anode.

5. A mercury vapour discharge device comprising in a vessel a mercury cathode, an annular anode in a plane parallel to the mercury surface, cathode plates on both sides of said anode and parallel thereto, the cathode plate nearer to the mercury level being at a distance less than 10 mm. therefrom, and a magnet so positioned with respect to said elements, that the field of it passes through said cathode plates at right angles with their surface, the mercury cathode and the cathode plates being connected through a resistor.

6. A mercury vapour discharge device comprising in a vessel a mercury cathode, an annular anode in a plane parallel to the mercury surface, cathode plates on both sides of said anode and parallel thereto, the cathode plate nearer to the mercury level being at a distance less than 10 mm. therefrom, and a magnet so positioned with respect to said elements that the field of it passes through said cathode plates at right angles with their surface, the mercury cathode and the cathode plates being connected through a resistor placed inside the vessel.

7. A mercury vapour discharge device comprising in a vessel a mercury cathode, a plurality of annular anodes in planes parallel to the mercury surface, centrally perforated cathode plates alternated with said anodes and parallel thereto, the cathode plate nearer to the mercury level being at a distance less than 10 mm. therefrom, and a magnet so positioned with respect to said elements that the field of it passes through said cathode plates at right angles with their surface.

8. A mercury vapour discharge device comprising in a vessel a mercury cathode, an annular anode in a plane parallel to the mercury surface, cathode plates on both sides of said anode and parallel thereto, the cathode plate nearer to the mercury level being at a distance less than 10 mm. therefrom, and a magnet so positioned with respect to said elements that the field of it passes through said cathode plates at right angles with their surface, the mercury cathode and the cathode plates being connected through a variable resistor.
